UNITED STATES PATENT OFFICE.

BAPTISTE F. CANAVERA, OF ST. LOUIS, MISSOURI.

BRICKKILN.

Application filed January 2, 1923. Serial No. 610,283.

To all whom it may concern:

Be it known that I, BAPTISTE F. CANAVERA, a citizen of the United States, residing at St. Louis and State of Missouri, have invented certain new and useful Improvements in Brickkilns; and I do declare the following to be a full, clear, and exact description of the invention, such as will enable others skilled in the art to which it appertains to

10 make and use the same.

My invention has for its object to generally improve upon and simplify the construction shown by my United States Patent No. 1,117,783 of November 17, 1914.

15 With the foregoing in view, the invention resides in the novel subject matter herein-after described and claimed, the description being supplemented by the accompanying drawings.

20 Figure 1 is a horizontal sectional view partly in elevation.

Figure 2 is a vertical transverse sectional view as indicated by line 2—2 of Fig. 1.

25 Figure 3 is a longitudinal sectional view through the center of the kiln, as indicated by line 3—3 of Fig. 1.

In the drawings above briefly described, the numeral 1 designates a straight central wall whose lower portion 2 is solid, with the exception that it is provided with vertically spaced passages 3, the upper portion however of said wall being hollow, in order to provide a longitudinal flue or smoke gallery 4 having a suitable stack 5. The inner side 30 of the crown 6 of the sleeve, preferably inclines to the stack in the manner shown in Fig. 3 or in a similar way, in order to increase the draft of the kiln.

35 A continuous tunnel 7 surrounds the central wall 1 in spaced relation therewith and the space between said tunnel and wall is filled with sand or the like as indicated at 8. A continuous wall 9 preferably surrounds the tunnel 7 and the space between this tunnel and wall is also filled with sand or other suitable insulator as indicated at 40 10.

The outer side of the tunnel 7 and the wall 9 are formed with spaced openings 11 45 through which the ware may be taken into the tunnel and removed therefrom. These openings are also used for building temporary fires to serve as pilots for powdered coal or similar fuel which may be fed to the tun-

nel through vertical openings 12 in its crown. 55 At a suitable time, the openings 11 are sealed by spaced inner and outer walls 12 and 12' which may be built therein from brick or any other suitable material, the space between each wall 12 and the adjacent wall 60 13 being filled with sand. For supplying the sand to the several spaces, I provide a plurality of upright tubular sand hoppers 14 over the several openings 11.

The bottom of the tunnel 7 is formed with 65 a plurality of down-draft flues 15 which discharge into the passages 3, communication between these passages and the flue 4 being controlled by appropriate dampers or valves 16 which may well have operating rods 17 70 rising through the crown 6. At times, when the valves 16 are closed, it is desirable to have the draft from the tunnel 7, pass through the fuel feeding openings 12 and from them to the flue 4. In order that this 75 may be done, I provide the crown 6 with a plurality of openings 18 and employ transverse conduits 19 resting removably upon the crowns of the tunnel 7 and the flue 4, the outer ends of said conduits being in communication with the openings 12, while the inner ends thereof open into the openings 18. When these conduits are not in use, they 80 may be moved out of operative position.

In operating the kiln, the ware is stacked 85 in the tunnel 7 and the pilot fires are built at the openings 11. When these fires have gained sufficient headway, coal dust or similar fuel is fed to the tunnel through the openings 12 to generate the requisite heat 90 for burning the ware. The openings 11 may then be closed by the walls 12 and 13 and the sand insulator between them. During one stage of the burning operation, the draft may take place through the flues 15 and passages 3 to the flue 4, the valves 16 being then opened. At another stage of the burning operation, however, the valves 16 are closed and the conduits 19 are disposed in operative 95 position so that the products of combustion 100 pass upwardly through the openings 12, then inwardly through the conduits, and will enter the flue 4 through the openings 18.

By employing the construction shown and described, the kiln shown by my former 105 patent is generally improved upon and simplified and while excellent results may be obtained from the details disclosed, it is to

be understood that within the scope of the invention as claimed, minor changes may be made.

The numerals 20 merely designate suitable clean-out manholes for the flue 4.

I claim:

1. A kiln comprising a central wall whose upper portion is hollow and forms a horizontal flue leading to a stack, the lower portion of said wall having vertical passages in valved communication with the flue and the upper portion of the wall having inlet passages; a continuous tunnel surrounding said central wall and having down-draft flues in its bottom discharging into said vertical passages, the outer wall of said tunnel having temporary fire openings while the crown of said tunnel is formed with fuel feeding openings; and 20 arched transversely disposed conduits rest-

ing removably on and extending between the crowns of said tunnel and said horizontal flue, said conduits being in communication with said fuel feeding openings and the upper inlet passages of said horizontal flue whereby to establish communication between the upper portion of the tunnel and the horizontal flue when said conduits are in place.

2. A kiln comprising a burning chamber having an opening in its outer wall through which the ware is carried into and removed from said chamber, said wall having a sand hopper over said opening for discharging sand into space between inner and outer temporary walls built up in said opening to close the same.

In testimony whereof I have hereunto affixed my signature.

BAPTISTE F. CANAVERA.
